Inventor,

Byron G. Knapp,
for *R. G. Knapp*,
his Attorney,

UNITED STATES PATENT OFFICE.

BYRON G. KNAPP, OF SANDY HILL, NEW YORK.

HITCHING-POST.

SPECIFICATION forming part of Letters Patent No. 399,904, dated March 19, 1889.

Application filed January 21, 1889. Serial No. 296,994. (No model.)

To all whom it may concern:

Be it known that I, BYRON G. KNAPP, a citizen of the United States, residing at Sandy Hill, in the county of Washington and State 5 of New York, have invented certain new and useful Improvements in Hitching-Posts; and I do hereby declare the following to be a full, clear, and exact description of the invention, such as will enable others skilled in the art 10 to which it appertains to make and use the same.

My invention relates to that class of hitching-posts in which the post is adapted to be elevated when in use and to be dropped down 15 into a tubular sheath set in the ground when not in use.

The object of my invention is to provide a locking-latch which will more effectually retain the post in elevated adjustment, a further object being to tightly close the mouth of the sheath when the post is down and out of use; and with these ends in view my invention consists in the peculiar features and combination of parts more fully described 25 hereinafter, and pointed out in the claim.

Referring to the accompanying drawings, Figure 1 represents a sectional elevation of my device, in which the movable post is shown raised as when in use; and Fig. 2, a similar view, in which the post is dropped down into the sheath when out of use.

The reference-letter *a* denotes a tubular sheath sunk below the surface of the ground. This sheath is given a size sufficient to receive 35 a vertically-movable post, *b*, which can be raised and lowered within it. The top of the sheath is provided with an annular flange or deflector, *c*, having upon its upper surface an annular bead, *d*, surrounding the orifice *f* 40 in the center of the deflector, through which the post passes and operates.

The post *b* consists simply of a hollow metallic tube having upon its upper extremity the usual strap-ring *g*, which ring is surrounded by a convex cap *b'*, the under side 45 of which is provided with an annular recess of a size and shape adapted to receive the bead *d*, in order that the cap may become closely seated upon the flange or deflector *c*.

The top of the post-cap is made convex, in order that its contour will coincide with the beveled edges of the deflector, to form a con-

tinuous convex water-shed or deflector when the post is down within its sheath and out of use, in which position it is shown in Fig. 2. 55

A gravitating latch, *h*, is pivoted within the tubular post and lies diagonally across the same, so that the opposite ends *i* and *j* will project through the perforations *k* and *k'*. This latch is pivoted just off the longitudinal 60 center of the post, and the pivot *l* passes through the offset *m*, so that the latch, by reason of the gravity of its upper end, will drop into locking adjustment when the post is elevated, as in Fig. 1. In this position the 65 lower end, *i*, is shown engaging the annular bead *d* through the medium of the recess *n*, which receives the bead and forms a sure and positive lock. When the post is in raised adjustment, the upper edge, *o*, of the lower portion of the latch comes in contact with the top edge, *p*, of the lower recess or perforation, *k*, in which position the recess *n* will come directly over and engage the bead *d*. This operation is caused by hanging the latch 70 off its center of gravity, so that the weight of its upper end will preponderate and keep its lower locking end constantly pressing outward. Therefore as soon as the post is raised to the limit of its upward movement and the 75 lower end of the latch becomes freed from the sheath, against which it has been constantly pressing, it will immediately spring out through the lower perforation and be in a position ready to engage the bead, and when 80 this operation takes place the upper end, *j*, will project through the upper perforation, *k'*. In lowering the post, the operator raises it a little to free the lower end from the bead *d*, and then pushes against the upper end, *j*, 85 which operation causes both ends to simultaneously retreat within the recesses of the post, and hence below the exterior surface thereof, to leave the post free to slide up and down within its sheath. It is readily seen 90 that this arrangement possesses many advantages over posts of this kind formerly in use, because there are few parts to become worn and disordered and its operation is more sure and simple. When the post is 95 dropped down within its sheath, the cap upon its upper extremity fits snugly down upon the flange upon the sheath and forms a continuous convex outer surface and a tight joint,

which sheds water and keeps dirt out of the sheath.

Having thus described my invention, what I claim as new, and desire to secure by Letters Patent, is—

The combination, in a hitching-post, of a tubular sheath adapted to be set in the ground, a flange or shed surrounding its upper extremity, an annular bead upon the upper surface of said flange, a tubular post arranged to slide vertically within said sheath, said post having perforations in its opposite sides, a gravitating locking-latch pivoted off the longitudinal center of the post, said

latch having a recess in its lower end, and a cap upon the top of the post, said cap being provided with an annular recess upon its under surface to receive the bead upon said flange, all arranged and adapted to operate in the manner and for the purpose substantially as described.

In testimony whereof I affix my signature in presence of two witnesses.

BYRON G. KNAPP
